Primary Examiner — Deanna L Pratt*Assistant Examiner* — Lilyana Bekic(74) *Attorney, Agent, or Firm* — Fishman & Associates, LLC(57) **CLAIM**

The ornamental design for a nozzle, as shown and described.

DESCRIPTION

FIG. 1 is a perspective view of the nozzle;

FIG. 2 is a side view of the nozzle;

FIG. 3 is an opposite side view of the nozzle;

FIG. 4 is a back view of the nozzle;

FIG. 5 is a front view of the nozzle;

FIG. 6 is a top view of the nozzle; and,

FIG. 7 is a bottom view of the nozzle.

The broken lines in the drawings depict environmental subject matter and form no part of the claimed design.

1 Claim, 6 Drawing Sheets
